Primary Examiner — David G Muller*Assistant Examiner* — Nathan M Johnston(74) *Attorney, Agent, or Firm* — Fay Kaplun & Marcin, LLP(57) **CLAIM**

The ornamental design for a CO2 absorber, as shown and described.

DESCRIPTION

FIG. 1 is a perspective view of a CO2 absorber showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In the drawings, the broken lines are shown for the purpose of illustrating environment only and form no part of the claimed design.
